[57] CLAIM

The ornamental design for a wire stretcher, as shown and described.

DESCRIPTION

FIG. 1 is a perspective view taken from the top, front and right side of the wire stretcher showing our new design; FIG. 2 is a right side elevational view thereof, the left side being the same as the right; FIG. 3 is a front end elevational view thereof; FIG. 4 is a rear end elevational view thereof; FIG. 5 is a top plan view thereof; and, FIG. 6 is a bottom plan view. FIGS. 2-6 are shown in a reduced scale relative to FIG. 1.
